UNITED STATES PATENT OFFICE.

TOIVO LEMPIE, OF MONTESANO, WASHINGTON.

REVOLVER-HANDLE.

1,279,372.

Specification of Letters Patent. Patented Sept. 17, 1918.

Application filed June 18, 1918. Serial No. 240,598.

To all whom it may concern:

Be it known that I, Toivo LEMPIE, a citizen of the United States, residing at Montesano, in the county of Grays Harbor and State of Washington, have invented new and useful Improvements in Revolver-Handles, of which the following is a specification.

This invention relates to auxiliary or target handles for pistols adapted to be secured to the handle frame of a pistol after the ordinary cheek pieces or stocks have been removed therefrom.

An object of the invention is to enlarge the handle to provide a broader and firmer grip on the weapon.

A further object of the invention is to produce an auxiliary pistol stock designed to raise the point of the weapon a little higher than the grip which goes with the gun, and therefore permit of the weapon to be sighted in an easier manner than by the employment of the ordinary stock or grip.

It is a still further object of the invention to produce an auxiliary or target handle for pistols which may be readily attached to the frame of any ordinary pistol, by simply removing the cheek pieces therefrom, and which will wholly inclose the handle frame and contact with the trigger guard, so that the trigger actuating finger of the operator will be guided in a natural manner to proper operating position, and also whereby the remaining fingers of the hand of the operator will grip the stock in a firmer and better manner.

Other objects of the invention will appear as the nature of the improvement is better understood, reference being had to the drawings, in which—

Fig. 1 is a side elevation of the frame of a pistol showing the improved auxiliary or target handle applied thereto;

Fig. 2 is a substantially similar view, with one of the sides of the target handle removed;

Fig. 3 is a transverse sectional view approximately on the line 3—3 of Fig. 1; and

Fig. 4 is a perspective view of one of the sections of a handle looking toward the inner base thereof.

In the drawings I have illustrated a portion of a pistol, which is indicated by the numeral 5. The handle frame of the pistol is indicated by the numeral 6, and the guard for the trigger by the numeral 7.

The handle stock is centrally cut away in the usual manner for lightness and for mechanical purposes, and is provided at its lower portion with laterally extending pins. 60 The improved stock or grip comprises two substantially similar sections each indicated by the numeral 9. These sections, when associated entirely receive the frame 6, and provide the pistol with what is known as a 65 square butt stock. Each of the sections 9, upon its inner face is provided with a depression of a depth approximately equalling one-half of the thickness of the pistol frame 6, and is of a width corresponding to that 70 of the pistol frame. These depressions are indicated by the numeral 10, and an inner wall of each of the depressions adjacent to the bottom wall thereof is provided with a recess 11, adapted to receive the pins 8. Both 75 of the members 9 are provided with openings, one of which is threaded and the other reamed from the outer face of the member. Passing through these openings, and through the central cut-away portion in the pistol 80 frame 6 is a headed screw 12, the head of the screw referred to being in the reamed portion in one of the stock members and the thread of the screw co-engaged with the threads in the opening of the other stock 85 member.

The upper wall of the recess portion 10 is rounded, as at 13, and this rounded portion is designed to be received in the curved depression 14, provided on the pistol frame 90 at the juncture of the handle portion 6 therewith. The inner face of each of the stock members 9, above the rounded wall or shoulder 13 is further depressed, as at 15, and the inner edge of each of the stocks, at the upper corner thereof, is provided with a rounded extension 16, the lower wall provided by the depression 15 being curved or rounded as at 17, from the rounded shoulder 13, over the referred to extension 16. This portion 100 17 is designed to conform to the shape of the trigger guard 7 at the inner end thereof, and the construction of the stock or cheek pieces 9 builds out the handle portion of the pistol. 105

It will be observed that the auxiliary stock permits of the user obtaining a better grip on the pistol, and guides his index finger to proper engagement with the trigger. The cheek pieces 9 may be made of wood, or any other desired material. The cheek may be cheaply constructed and easily applied, and it is believed that the advantages of the im- 110

provement will be apparent without further detailed description.

Having thus described the invention, what is claimed as new, is:—

- 5 In a pistol stock, the combination with the frame of a pistol handle having lateral shoulders at the upper end thereof provided with depressions and being further provided with lateral pins, of cheek pieces for the
10 handle each having its inner face recessed a depth approximately equaling one-half of the thickness of the handle and conform-

ing to the contour of the frame, said cheek pieces having depressions to receive the pins on the handle, said cheek pieces, at the upper ends thereof having extensions received in the referred to recessed portions in the shoulders of the handle and to receive the inner portion of the trigger guard of the pistol and removable means for securing the 20 cheek pieces to the frame.

In testimony whereof I affix my signature.

TOIVO LEMPIE.

Copies of this patent may be obtained for five cents each, by addressing the "Commissioner of Patents, Washington, D. C."
